UNITED STATES PATENT OFFICE.

GEORGE HERMAN BUGENHAGEN, OF MINOT, NORTH DAKOTA.

LAWN-SWING.

1,364,610.

Specification of Letters Patent.

Patented Jan. 4, 1921.

Application filed August 13, 1919. Serial No. 317,199.

To all whom it may concern:

Be it known that I, GEORGE H. BUGENHAGEN, a citizen of the United States, and a resident of the city of Minot, in the county of Ward and State of North Dakota, have invented a new and useful Improvement in Lawn-Swings, of which the following is a full, clear, and exact description.

My invention relates to improvements in lawn swings, and it consists in the combinations, constructions and arrangements hereinafter described and claimed.

An object of my invention is to provide a device which is simple in construction, easily operated, and is not liable to get out of order.

A further object of my invention is to provide a lawn swing which is rigidly supported, and which is provided with seats for one or more occupants, each of which may assist in propelling the swing.

A further object of my invention is to provide a device of the type described in which the propulsion of the swing may be effected by means of the hands and feet.

Other objects and advantages will appear in the following specification, and the novel features of the invention will be particularly pointed out in the appended claims.

My invention is illustrated in the accompanying drawing, which is a perspective view of the swing.

In carrying out my invention, I provide four supporting posts 1, which are joined together at their tops by any suitable fastening means 2. Extending transversely with respect to the posts are two parallel suspension bars 3 and 4 respectively, these bars being braced at their ends by inclined braces 5 and 6. Horizontally placed bars 7 and 8 are also provided, as clearly shown in the drawing. The bars 3 and 4, together with the bars 5, 6, 7 and 8 form a supporting frame.

The carrier is formed by two parallel side pieces 9 and 10, bearing seats 11, which may be arranged in tandem or facing one another, as shown. The carrier thus formed is pivotally suspended at its ends by means of suspension bars 12 and 13 from the ends of the bars 3 and 4. Strengthening braces 14 are provided near the upper ends of the suspension bars 12 and 13. Pivot rods 15 are provided for spacing the ends of the frame bars 3 and 4, and for pivoting the suspension bars 12 and 13 thereto.

One set of suspension bars is extended below the pivotal connection 16 with the carrier frame. To the ends of these extended suspension bars is pivotally connected a pair of propulsion bars 17 and 18. The latter have connected with them at one or more points levers 19 which are pivoted at 20 to the carrier frame, and which have pivotal connections to the bars 17 and 18, as shown. These levers are formed by separate pieces which are connected to the carrier frame. At the upper end of the levers are the cross rods 21, which form operating handles, while at the lower ends are cross rods 22 which form foot rests.

From the foregoing description of the various parts of the device, the operation thereof may be readily understood. The operator 23 seated in the carrier with his hands on the bar 21 and his feet on the bar 22, pulls the handle 21 toward him and pushes with his feet. This tends to apply a force to the suspension bars 12 and 13 to swing them outwardly. At the end of the outward movement, the operator pushes on the bar 21, tending to propel the swing in the other direction. By alternately pushing and pulling, the swing acquires a greater movement.

The power ratio may be changed to any desired ratio by simply having a series of holes in the suspension member, so that the large or short lever arm is obtained below the carrier, thus making the power adaptable to one operator or to any number of operators.

While I have described one particular form of the invention, it is obvious that the same principle might apply to many different forms and sizes without departing from the spirit of the invention.

I claim:

1. A lawn swing having rigid inclined supporting posts connected together at a common point at their tops, a supporting frame carried by said posts, said frame comprising a pair of parallel supporting bars arranged to lie in the same horizontal plane and being connected adjacent their middle portions to the said supporting posts near the upper ends of the latter, a second pair of parallel supporting bars arranged to lie in a lower horizontal plane than the first named parallel supporting bars and having their ends secured to said supporting posts, and inclined bracing bars connecting the

- ends of said first named supporting bars and said second named supporting bars, a carrier, suspension bars pivotally secured to said carrier and having their upper ends 5 pivotally connected to the ends of said first named parallel supporting bars, certain of said suspension bars being extended below the carrier, a lever fulcrumed on said carrier, said lever comprising spaced bars having connecting rods at each end, one of said connecting rods serving as a hand bar and the other as a foot rest, and rigid connecting links extending from the lower end of said lever to said suspension bars.
- 10 15 2. A lawn swing having rigid inclined supporting posts connected together at a common point at their tops, a supporting frame carried by said posts, said frame comprising a pair of parallel supporting bars arranged to lie in the same horizontal plane and being connected adjacent their middle portions to the said supporting posts near the upper ends of the ladder, a second

pair of parallel supporting bars arranged to lie in a lower horizontal plane than the 25 first named parallel supporting bars and having their ends secured to said supporting posts, and inclined bracing bars connecting the adjacent ends of said first named supporting bars and said second named supporting bars, a rectangular carrier, suspension bars pivotally secured to said carrier and having their upper ends pivotally connected to the ends of said first named parallel supporting bars, certain of said suspension bars being extended below the carrier, a lever fulcrumed on said carrier, said lever comprising spaced bars having connecting rods at each end, one of said connecting rods serving as a hand bar and the 40 other as a foot rest, and rigid connecting links connecting the lower end of said lever to the lower ends of the extended suspension bars.

GEORGE HERMAN BUGENHAGEN.
